UNITED STATES PATENT OFFICE.

AUGUST HIEBER, OF CANNSTATT-STUTTGART, GERMANY.

SLIDING WINDOW CONTROLLED BY SPIRAL SPRING.

Application filed August 3, 1921. Serial No. 489,636.

To all whom it may concern:

Be it known that I, AUGUST HIEBER, a citizen of the Republic of Germany, residing at Cannstatt-Stuttgart, Wurtemberg, Germany, have invented certain new and useful Improvements in Sliding Windows Controlled by Spiral Springs, of which the following is a specification.

This invention relates to an improvement in the construction of a sliding window which is held at any position by a spring controlled bell crank lever.

The improvement consists in the special manner of regulating the tension of the spring so that it corresponds always with the actual weight of the window and further in the special construction of the lever which is arranged so that in certain end positions this lever acts as a rigid but spring controlled element and that in other end positions of said lever the action of the spring is neutralized by the position of the parts of the lever, with regard to each other and with regard to the direction of movement of the window. In this latter case the spring can no longer lift or lower the window which is thus secured in its position.

The adjustability of the tension of the spring is obtained by giving to the spring casing a square cross section and by removably mounting said casing in a holder fixed to the wall, said casing having an abutment adjustable upon the spring axle, the bell crank lever being pressed against said abutment by the action of the spring. In order to alter the tension of the spring it is merely necessary to adjust the abutment and to push the casing, after it has been turned, e. g., for 90°, into the holder which for this purpose is preferably open at the side.

In order to neutralize the action of the spring in certain positions the two parts of the lever are connected the one with the other and with the window in such a manner that both parts point either in the direction of the movement of the window or that the joint of the lever is depressed perpendicularly to the direction of movement of the window. On one of the parts of the lever an abutment is arranged so that it comes in contact with the other part of the lever when the two parts of the lever are in a determined position, so that the two parts of the lever act like a rigid lever in

one direction, being however still spring controlled.

In order that the invention may be clearly understood, I shall proceed to describe the same with reference to the forms of construction shown by way of example in the accompanying drawing, wherein:—

Fig. 1 shows in front elevation a window in closed position.

Figs. 2 and 3 are side elevations of Fig. 1 showing the window respectively closed and open.

Fig. 4 shows the window in side elevation, the lower sash being brought to the horizontal position to be cleaned.

Fig. 5 is a horizontal section on a larger scale showing the spring housing mounted in the frame.

Figs. 6 and 7 are front views respectively of a small end of a large carriage window 75 with one and with two adjusting devices.

Fig. 8 is a vertical section of Figures 6 or 7.

Fig. 9 shows on a larger scale a section through the spring housing taken perpendicularly to the pivot axle.

Figs. 10 and 11 are respectively a plan view and an axial section through the adjusting device.

The lower sash *a* of the window has laterally projecting stubs *b* adapted to slide in guide grooves *c* which are essentially vertical but bent at the lower end as shown by Figures 2-4 towards the fixed sash *d*.

For fixing the sliding sash *a* at any position the spiral spring *e* is provided which is fixed with one end in its housing *g* and with its other end on a revolvable axle *h* (Fig. 9). This axle *h* is mounted with one end in the rear wall of the housing for the spiral spring. Upon the spring axle *h* the locking lever of the window sash *a* is fixed which consists of two parts *k* and *l* pivotably connected the one with the other. The part *k* which acts as a lever arm is mounted upon the axle *h*, the part *l* pivotably connected with part *k* by a pivot bolt *m* being connected with the window sash *a* by a laterally projecting stud *n* of said sash projecting through a slot *o* of the part *l*.

The slot *o* serves to permit the lifting of the window sash for such a distance that (e. g., with windows for railway cars Figures 6 and 7 or with sliding windows as shown by Fig. 2) the window sash can be lifted over

105
110

the weather ledge without the aid of the spring.

The housing *g* of spring *e* is of square cross section (Fig. 9) and it is located in a holder *q* fixed in the frame *p* of the window, said holder being open at the side so that housing after having been turned for 90° can be inserted in said holder. For regulating the tension of the spring *e* a stop *r*, e. g., a screw, is arranged upon the cover plate *i* of the housing. Four holes *s* in the cover plate *i* are designed to receive said stop. The head of the screw *r* serves as abutment for the lever *k* fixed upon the spring axle *h* and pressed against this abutment through the action of the spring. When the tension of spring *e* has to be increased, if for example the window sash *a* is of greater weight than usual, the lever *k* has been turned and the housing *g* after having been turned for 90° is inserted in the holder *q*.

The lever *k* has further a counter bearing *t* (see Figures 9 and 10) which grips behind the part *l* when the two parts *k*, *l* have adopted a determined position (see Figs. 3 and 4) so that the jumping over of the dead point position is prevented. The two parts *k* and *l* then form a rigid system which is however still controlled by the spring *e*.

The two parts *k*, *l* of the lever are constructed and connected with the window sash *a* in such a manner that, the action of the spring is neutralized when the window sash is in the closed or in the open position. As shown in Fig. 2 the parts *k* and *l* can be brought into such a position that they are both situated approximately in the direction of the movement of the window sash and that the action of the spring is neutralized, an abutment *u* of part *l* prevents the excessive turning of the lever. Figs. 6 and 7 show in dot and dash lines how the action of the spring is neutralized by the part *l* being pressed by the part *k* or by the spring *e* perpendicularly to the direction of movement of the window sash *a* so that the spring does enter into action only when the window sash *a* has been slightly lifted by hand so that the two parts of the lever are brought to the angular position the part *l* standing at an angle to part *k*.

Claims:

1. A sliding window controlled by a spiral spring comprising in combination with the window sash slideable in the window frame and with a spiral spring, a housing for said spring of square cross section, an axle for said spring fixed in said housing, a holder for said housing embedded in said window frame, a one armed lever fixed upon said axle of the spring, an upper arm pivotably connected with the upper end of said lever and having a slot at its upper end, a stud

projecting from the window sash engaging with said slot of the upper part of the lever and a stop for the lever adapted to be fixed in said spring housing at different positions with regard to the said spring axle. 70

2. A sliding window controlled by a spiral spring comprising in combination with the window sash slideable in the window frame and with a spiral spring, a housing for said spring of square cross section, an axle for said spring fixed in said housing, a holder for said housing open at the side embedded in said window frame, a one-armed lever fixed upon said axle of the spring, an upper arm pivotably connected with the upper end of said lever and having a slot at its upper end, a stud projecting from the window sash engaging with said slot of the upper part of the lever and a stop for the lever adapted to be fixed in said spring housing at different positions with regard to the said spring axle. 75

3. A sliding window controlled by a spiral spring comprising in combination with the window sash slideable in the window frame and with a spiral spring, a housing for said spring of square cross section, an axle for said spring fixed in said housing, a holder for said housing embedded in said window frame, a one-armed lever fixed upon said axle of the spring, an upper arm pivotably connected with the upper end of said lever and having a slot at its upper end, a stud projecting from the window sash engaging with said slot of the upper part of the lever, an abutment upon said upper part of the lever serving to lock said part and said lever so that they form one rigid part when they are at a determined position and a stop for the lever adapted to be fixed in said spring housing at different positions with regard to the said spring axle. 80 85

4. A sliding window sash, a spiral spring, a member adapted for rotation by said spring, a lever fixed upon said member, an arm pivotally connected to the lever remote from the spring, said arm having a slot in its free end to provide for connection with the sliding window, and a stop arranged adjacent the spring to limit the movement of the lever under the influence of the spring, said stop being adapted for a variety of positions to variously limit the movement of the lever. 90 95 100 105

5. A sliding window sash, a spiral spring, means whereby said spring may be tensioned, a lever adapted to be operated by said spring, said spring tensioning means including an element to serve as a limit stop for the movement of the lever in one direction, an arm pivotally connected to the free end of the lever and also movably connected to the window sash, and means whereby said arm and lever when in a predetermined position are held in relatively rigid relation. 110 115 120 125 130

tion while still subjected to the action of the spring.

6. A sliding window sash, a spiral spring, a member adapted for rotation by said spring, a lever fixed upon said member, an arm pivotally connected to the lever remote from the spring and adapted for relatively rigid relation to the member in a predetermined position of the arm and lever, and

means for adjusting the tension of the spring ¹⁰ while permitting the limit movement of the lever under the influence of the spring.

In testimony whereof I affix my signature in presence of two witnesses.

AUGUST HIEBER.
